PROPELLING MECHANISM

Charles A. Massey, Norman, Okla.

Application January 21, 1939, Serial No. 252,191

1 Claim. (Cl. 170—150)

This invention relates to a propelling mechanism particularly designed and adapted for use in connection with watercraft and aircraft, and it is an object of the invention to provide a mechanism of this kind operating in the general fashion of a paddle wheel and wherein are employed blades mounted in a manner whereby the angle of the blades can be readily changed at will while the mechanism is in operation or otherwise.

10 The invention also embodies a mechanism of this kind comprising a driven rotatable member carrying a plurality of blades each of which has its central portion rotatably engaged with the member and wherein means are provided to effect a one-half revolution of each of the blades to a single revolution of the rotatable member.

15 The invention consists in the details of construction and in the combination and arrangement of the several parts of my improved propelling mechanism whereby certain important advantages are attained and the device rendered simpler, less expensive and otherwise more convenient and advantageous for use, as will be hereinafter more fully set forth.

20 25 The novel features of my invention will hereinafter be definitely claimed.

In order that my invention may be the better understood, I will now proceed to describe the same with reference to the accompanying drawing, wherein:

30 Figure 1 is a fragmentary view in perspective illustrating a propelling mechanism constructed in accordance with an embodiment of my invention;

35 Figure 2 is an enlarged fragmentary view partly in elevation and partly in section illustrating certain features of the mechanism as herein comprised;

40 Figure 3 is a detailed sectional view taken substantially on the line 3—3 of Figure 1.

45 As disclosed in the accompanying drawing, P denotes a platform or other support comprised in the structure of a watercraft or aircraft and disposed transversely thereof by the blocks 1 are the housings 2 at opposite sides of the gear casing 3. Rotatably disposed thru the housings 2 is a shaft 4 of desired length and which has each end portion extending a desired distance outwardly beyond the adjacent side of the platform 50 P. The shaft 4 is in driven connection with a power shaft 5 of conventional gearing arranged within the casing 3. It is to be stated at this time that the means for rotating the shaft 5 in its details forms no part of the present invention.

55 Mounted upon each extended end portion of the shaft 4 is a rotatable member R of desired dimensions. This member R constitutes a casting and comprises the spaced circular side plates 6 having interposed between the peripheral portions thereof a closing sleeve or annular member 7. These plates 6 and member 7 are maintained in assembled relation in any desired manner, such as by conventional bolts 8.

10 The plates 6 of each of the rotatable members R at the axial centers thereof are provided with the openings 9 and 10 through which the extended end portion of the shaft 4 snugly passes. The opening 9 in the outer plate 6 snugly receives the shaft 4, and locked, as at 11, to the outer face of the outer plate 6 is a hub sleeve 12 defining the opening 9 and through which hub sleeve 12 the shaft 4 also snugly passes. This hub sleeve 12 is provided with means, such as the binding screw 14, for locking the hub sleeve 15 to the shaft 4, whereby said shaft 4 and the rotatable member R are connected for unitary rotation in the same direction.

15 Each end portion of the housing 2 is provided with an elongated bearing sleeve 15 for the adjacent portion of the shaft 4 and this sleeve, when applied, is of a length to extend within the member R through the opening 10 in the inner plate 6 of the member R. Freely mounted on the bearing sleeve 15 for rotation therearound is 20 a second sleeve 16 which also extends within the member R through the opening 10 but which is also disposed as desired beyond the opposite faces of the inner plate 6.

25 Keyed, as at 17, to the portion of the sleeve 35 16 extending outwardly beyond the inner plate 6 of the member R is a gear wheel 18 of desired size and with which engages an elongated rack 19 having endwise movement in a direction at right angles to the shaft 4.

30 35 Each of these racks 19, as herein disclosed, is properly supported in desired placement by the upstanding guide brackets 20 carried by the platform P and the two rack members 19 are connected for unitary movement by the cross member or strip 21. One end portion of the cross member 21 is formed to provide a bracket 22 with which is pivotally connected, as at 23, a hand lever 24. As illustrated in Figure 1, this hand lever 24 is pivotally mounted, as at 25, on a support 26 positioned a suitable distance below the member 21. The lever 24 is continued below its pivotal mounting 25 and such depending arm 27 of the lever at its lower end carries a swinging dog 28 normally maintained in locking engagement 50 55

with the rack 29 by the coil spring 30 secured to one end portion of the dog 28 and to the arm 27.

The dog 28 is adapted to be disengaged from the rack 29 through the medium of the conventional release as illustrated at 31.

Rotatably supported by the plates 6 of each of the members R and bridging the space there-between are the shafts 32. These shafts 32 are equidistantly spaced at opposite sides of the shaft 4 and are in parallelism with each other and with the shaft 4. The shafts 32 and shaft 4 are also within the same radial plane.

The shafts 32 extend outwardly beyond the outer plate 6 of the rotatable member and fixed to said extended portions of the shafts 32 at their longitudinal centers are the relatively broad flat blades 33 of desired length. The outer or extended end portions of the shafts 33 are engaged with the extremities of the reinforcing member 34, the central portion of which is keyed or otherwise locked, as at 35, to the extremity of the shaft 4 outwardly of the adjacent member R.

Keyed, as at 36, or otherwise fixed to the sleeve 16 for rotation therewith are the sprockets 37 arranged side by side and of the same size. Fixed to the shafts 32 within each of the rotatable members R are the sprocket wheels 38, said wheels 38 and sprockets 37 being of a ratio of two to one with the wheels 38 being the largest.

Engaged around each of the sprocket wheels 38 is a sprocket chain 39 which is also disposed around one of the sprockets 37.

It is believed to be obvious that as the members R make a single revolution the blades 33 will swing 180°, and it is to be further stated that in the assembly of each pair of blades 33 the relation will be such that when one of the blades is in a horizontal position the other will be in a vertical position as illustrated in the drawing. It is also believed to be obvious that upon proper manipulation of the lever 24, the angle of the blades 33 may be varied as desired independently of the members R and that such variations can be accomplished at will during the turning of the members R or when the same are at a standstill.

It is believed to be apparent that at every one-half turn of the member R the blades 33 are in perpendicular relation.

During each revolution of a member R the blades 33 carried thereby come into perpendicular relation for one-half turn of the member. In Figure 1 of the drawing, the lever 24 has been operated to turn the sleeve 16 and the sprockets 37 carried thereby to an extent to cause each of the blades 33 as it travels upwardly to assume a substantially vertical position and the second blade 33 to extend outwardly from the member R as it travels downwardly whereby the boat is

caused to travel in one direction. It is to be stated that the propelling mechanism when employed upon a water boat is in submergence. When it is desired to reverse the direction of travel of the boat, the lever 24 is shifted to rotate the sleeve 16 and the sprockets 37 to adjust the blades 33 so that as a blade 33 travels downwardly it is substantially vertically disposed and outwardly directed as it travels upwardly, thus causing the blade to have its propelling action above the shaft 4 instead of below which is the case when the blade is in the position first mentioned.

From the foregoing description it is thought to be obvious that a propelling mechanism constructed in accordance with my invention is particularly well adapted for us by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A propelling mechanism comprising a shaft, means for rotating the shaft, a casing mounted on the shaft, said casing comprising two spaced side plates connected for unitary rotation, means for securing one of the plates of the casing to the shaft, a sleeve freely mounted on the shaft and freely extending within the casing through the second side plate, shafts rotatably carried by the plates of the casing and bridging the space between said plates, said rotatably carried shafts extending outwardly beyond the plate of the casing fixed to the first named shaft, elongated blades having their central portions fixed to the extended portions of the rotatably carried shafts, said rotatably carried shafts being at opposite sides of the first named shaft and in parallelism therewith, a sprocket fixed to each of the rotatably carried shafts between the side plates of the casing, a pair of sprockets fixed to the sleeve and positioned between the side plates of the casing, sprocket chains connecting the sprockets of the sleeve with the sprockets of the rotatably carried shafts, the sprockets on the sleeve and the sprockets on the rotatably carried shafts being of a ratio, when the sprockets on the sleeve are held against rotation, of one to two respectively, means for rotating the sleeve independently of the first shaft and casing thereon for adjusting the angular relation of the blades, and means for locking the sleeve against rotation.

CHARLES A. MASSEY.
